Specification of Letters Patent.

Patented Nov. 25, 1913.

Application filed June 22, 1912. Serial No. 705,256.

To all whom it may concern:

Be it known that I, WILHELM SCHWARTZ, residing at Essen-on-the-Ruhr, Germany, a subject of the Emperor of Germany, have 5 invented a certain new and useful Improvement in Fuse-Setting Machines, of which the following is a specification.

This invention relates to fuse setters and aims to provide a device which makes it possible to give a series of different settings of slight difference to the fuses in a set of projectiles, as for instance would be required by scattered firing against airships.

One embodiment of the invention is illustrated in the drawing representing a fuse setting machine which in the usual manner is provided with an operating member mounted to turn in the housing for the purpose of setting the fuse and shows in Figure 20 1 an end view of the fuse setting machine; Fig. 2 a top view of Fig. 1; Fig. 3 a section along line 3—3 of Fig. 1, seen from the left; Fig. 4 a section along line 4—4 of Fig. 3, seen from the right, and Fig. 5 a section 25 along line 5—5 of Fig. 4, seen from above.

The fuse setting machine comprises the usual housing A wherein are mounted to turn the setting members B and C for the fuse parts, arranged coaxially, of which the 30 one member B is intended for engaging the adjustable fuse part and the other member C for engaging a part of the fuse body. For making the connection between the setting members and the corresponding fuse parts latches b¹ and c¹ are provided, actuated in the usual manner by a spring pressure and suitable notches on the fuse are provided for these latches. The setting member B has a toothed gear b² and the setting 35 member C a similar gear c². The toothed gears b² and c² are in mesh with two beveled gears D and E respectively which are mounted to turn in the housing A independently of each other around the same axis, 40 the beveled gear D meshing with the toothed gear b² and the beveled gear E with the toothed gear c². The beveled wheel D is fixedly connected with the crank F which forms the actuating member for setting the 45 fuse. The nave F¹ of the crank F is bell-shaped and on its front face closed by a cover plate f² which is rigidly connected thereto. The crank F has a projection f³, 50 see Fig. 2, which has a cone-shaped recess f⁴ 55 for a similarly shaped spring-actuated snap

latch a¹, which is situated in the housing A, and intended to hold the crank F yieldingly in the position shown on the drawing. Within the crank nave F¹ is arranged a worm wheel G which is rigidly connected 60 with the bevel wheel E. The worm wheel G engages a self-locking worm H, which worm is mounted on a shaft H¹ in the crank nave F¹. The worm gearing H G is intended to give to the setting member C the desired angular position corresponding to the distance of the detonating point relative to the setting member B. To make it possible to read the distance of the detonating point, a scale g², see Fig. 1, is provided on the disk 65 G¹ made in one piece with the worm wheel G; and a mark f⁶ inscribed on the edge of a window f⁵ cut in the cover plate f², through which window the scale g² is visible. A spur wheel J is furthermore provided in the 70 crank nave F¹ which is mounted to turn around an axis which is parallel to the axis of rotation of the crank F, and is in mesh with the toothed gear a², which latter is rigidly connected with the housing A. The 75 spur wheel J has in its middle a stud-shaft i¹ whereon two bevel wheels K and K¹ are rigidly connected with each other and so arranged that they are able to be displaced, on the one hand, in the axial direction on the 80 stub shaft i¹, and on the other hand are compelled to follow every turning of the spur wheel J and the stub shaft i¹. A sleeve M serves to axially displace the bevel wheels K 85 and K¹, which sleeve incloses a contracted part k² of the hub of the bevel wheel K. This sleeve M is displaceably mounted in an insertion piece f⁷, compare Fig. 4, which is rigidly connected with the crank nave F¹, 90 and this sleeve has a groove m¹ running at 95 right angle to the direction of displacement. A stud n¹ engages the groove m¹ which stud is arranged eccentrically on a shaft N, which shaft is carried in the insertion piece f⁷ and is provided with a crank-handle n², 100 so that by the turning of the shaft N the sleeve M, and with it the bevel wheels K and K¹, may be displaced in the direction of the axis of rotation of the spur wheel J.

Each of the two bevel wheels K and K¹ 105 is intended to engage in a bevel wheel P mounted to rotate on the insertion piece f⁷ and the arrangement of these parts is such that, with the angular position of the crank-handle n² as shown in the drawing and the 110

corresponding position of the sleeve M, only the bevel wheel K is in mesh with the bevel wheel P; and with the crank-handle n^2 turned around 180° only the bevel wheel K^1 is in mesh with said bevel wheel P. The two angular positions of the crank-handle n^2 are indicated by marks f^9 and f^{10} visible on the top cover f^8 , closing the crank nave F¹. Three spur wheels P¹, P² and P³ of different pitch diameters are rigidly connected with the bevel wheel P, which spur wheels are each in mesh with one of the three spur wheels Q, Q¹ and Q², see Fig. 4, which latter are mounted to turn independently of each other around the same axis as the shaft H¹. The spur wheel Q being in mesh with the spur wheel P¹, is rigidly connected with a follower Q³; the spur wheel Q¹ being in mesh with the spur wheel P² is rigidly connected with a follower Q⁴; and the spur wheel Q² being in mesh with the spur wheel P³ is rigidly connected with a follower Q⁵. All of these followers are provided with coupling teeth q^6 around their periphery on their front face, see particularly Fig. 5. These concentrically arranged toothed circles are separated from each other by means of narrow rings q^7 therebetween; moreover the outermost one of these toothed circles q^6 , situated on the follower Q⁵, is inclosed by a ring q^8 . The front faces of the toothed circles q^6 are all situated in the same plane and are covered by a flange h² situated on the shaft H¹. A sliding piece R is mounted on the flange h², displaceable in the radial direction, which slide piece is provided with a button r¹ serving as a handle. The sliding piece R is actuated by a spring T tending to draw the button r¹ toward the axis of rotation of the shaft H¹. The button r¹, being displaceable parallel to the axis of rotation of the shaft H¹ on a spindle r², is rigidly connected with a coupling pin r³, adapted to engage with each of the toothed circles q^6 , and actuated by a spring r⁴. The flange h² of the shaft H¹ is covered by a cap h³ which has a slot h⁴ for the spindle r² and a knob r⁵ on the back of the sliding piece R; the mantle part of this cap also inclosing the polished surface of a rib f¹¹ on the cover plate f⁸. When the sliding piece R is situated in its extreme inner position, as shown in Fig. 4, the coupling pin r³ will engage in the toothed circle of the inner follower Q³, and as a consequence the engagement in a great number of different angular positions of the shaft H¹ can be obtained, depending on the number of teeth of the toothed circle q^6 . As soon as the sliding piece R is pushed outward against the action of the spring T, after the coupling pin r³ has been brought out of engagement with the toothed circle of the follower Q³ by drawing out the button r¹, the coupling

pin r³ may thereupon be brought into engagement with the toothed circle of the follower Q⁴ or Q⁵ whereby even a greater number of separate angular positions of the shaft H¹ is attainable. Should now the coupling pin r³ be in engagement with the toothed circle of one of these two followers, it will, by the pressure of the spring T, simultaneously lie against the outside of that ring q^7 , which is situated on the inner side of the toothed circle in question, whereby the sliding piece R is immediately secured in its radial position. This sliding piece R will attain its outer extreme position when the coupling pin r³ stands above the smooth surface of the ring-shaped rib f¹¹ of the cover plate f⁸. In this position of the sliding piece R, in which it is secured by the ring q^8 , the worm shaft H¹ may be rotated independent of the followers Q³, Q⁴ and Q⁵. To indicate the different positions which the slide piece R may take up in radial direction, are provided four lines inscribed on the edge of the slot h⁴, namely h⁵, h⁶, h⁷ and h⁸, see Fig. 2, and a mark r⁶ on the knob r⁵; and here the marks h⁵ and h⁶ and h⁷ express the positions of the sliding piece R, wherein the coupling pin r³ has arrived in engagement with the toothed circle q^6 of one of the followers Q³, Q⁴ and Q⁵; and the mark h⁸ expresses the position wherein the coupling pin r³ stands over the smooth surface of the ring-shaped rib f¹¹.

In describing the action and the working of the above described fuse setting machine we will start from the position of the different parts represented in the drawings. Supposing to begin with that the projectiles are not to be set for scattered firing. In this case the sliding piece R is so adjusted that the mark r⁶, Fig. 2, registers with the line h⁸. In order to give the setting members B and C the angular position that corresponds to the desired distance of the detonating point, the shaft H¹ has then to be turned by means of the button r¹. This can be done without interference as the coupling pin r³ in the above mentioned position of the sliding piece R stands over the smooth surface of the ring-shaped rib f¹¹ of the cover plate f⁸. The turning of the shaft H¹ is transmitted by means of the worm H to the worm wheel G and thereby also to the disk G¹ which carries the scale g² and is built out of one piece with the worm wheel G and also to the toothed wheel E, rigidly connected thereto, and to the setting member C, connected therewith through the toothed circle c². As now the crank F and with it also the bevel wheel D, rigidly connected therewith, is held in position by means of the snap latch a¹, Fig. 2, the setting member B will remain at rest during the rotation of the shaft H¹ because the toothed circle b² 120

engages the locked bevel wheel D. The turning of the shaft H¹ continues until the division line of the scale g² registers with the mark f⁶, see Fig. 1, that corresponds to the desired distance of the detonating point. The setting member C does thereupon take an angular position corresponding to the desired distance of the detonating point relative to the setting member B. In order 10 now to set the fuse the projectile is inserted, as indicated in Fig. 3, by the dot and dash lines, into the fuse setting machine, whereupon the crank F is turned around completely once, after the snap latch a¹ has 15 been brought out of engagement with the cone-shaped recess f⁴ by means of a powerful pressure on the crank-handle. Besides the bevel wheel D, which is rigidly connected with the crank F, also the bevel wheel 20 E will follow in the rotation of the crank F, as the latter is coupled with the crank nave F¹ by means of the self locking worm gearing G H. The two setting members B and C will then be turned in opposite direction 25 to each other an angle of 360° relative to the housing A by means of the bevel gearing D d² and E e², whereby the fuse will be given the desired setting in well known manner. During the turning of the crank F the 30 spur wheel J rolls on the fixed toothed circle a² and is hereby turned around its axis. The turning of the spur wheel J is transmitted through the bevel gearing K P to the spur wheels P¹ P² and P³ and from 35 them to the spur wheels Q Q¹ and Q² as well as to the followers Q³ Q⁴ and Q⁵, so that the followers will revolve with different angular velocities, because the spur gearings P¹ Q, P² Q¹ and P³ Q² are all geared at different 40 ratio. As, however, in consequence of the before mentioned adjustment of the sliding piece R, the coupling pin r³ does not engage with any of the toothed circles q⁶ of the followers, it will follow that with 45 this adjustment the turning of the followers will have no influence on the operation of the machine. Should now scattering firing have to be done at the same range, the sliding piece R will be so adjusted that the coupling pin r³ engages one of the toothed circles q⁶, for example the toothed circle of the 50 follower Q³ as shown in Figs. 4 and 5 (after the shaft H¹, if necessary, has simultaneously been rotated a slight amount which is 55 without consequence for the adjustment of the fuse setting machine). The shaft H¹ will in this case follow the turning of the follower Q³ when the crank F is turned. In consequence thereof the setting members 60 B and C will have at the end of completion of the setting a somewhat different relative angular position than at the beginning, and the fuse will therefore be set to a distance of the detonating point that will deviate a 65 certain amount, for instance, 150 meters,

from that indicated on the scale g² at the beginning of the setting operation. At each following setting operation the then adjusted distance will be automatically changed 70 150 meters, that is, the set fuses will receive a scattering of 150 meters. Should the sliding piece R be so adjusted that the coupling pin r³ engages the toothed circle q⁶ of the follower Q⁴ or Q⁵, the consequence would be that the shaft H¹ will turn with different angular velocity than heretofore, because the gears K K¹ P P¹ P² P³ Q Q¹ Q² form change speed gears, and that therefore the distances which have been set in several adjusting operations after each other, will 75 change a different amount, for instance an amount of 100 or 30 meters respectively, when it is supposed in accordance with the ratio given in the drawing that the follower Q³ turns with the greatest angular velocity, the follower Q⁴ with the smallest and the follower Q⁵ with a mean angular velocity. Should the crank-handle n² be turned 180° out of its angular position indicated in Fig. 2, so that it stands over the mark f¹⁰, the sleeve M will be displaced so far in the direction of the arrow x, see Fig. 3, that the bevel wheel K¹ will arrive in engagement with the bevel wheel P, while the bevel wheel K will get out of mesh therewith. The followers Q³ Q⁴ and Q⁵, by the turning of the crank F, must now turn in the opposite direction to what they did heretofore, as the gearings K K¹ P form a change gear, so that by several repeated setting operations the 80 85 consequent adjustment of the distances will now be diminished the same amount as they were previously supposed to increase for the desired scattering. It will therefore be accomplished that the projectiles in a whole series of projectiles, may be set at widely different distances of detonating point, each one differing from the other in scattering, without any further adjustment of the fuse setting machine; as soon as the machine has 90 once been adjusted for a certain distance of detonating point indicated by the mark f⁶ of the scale g², and also adjusted for a certain scattering; the amount depending on the radial adjustment of the sliding piece 95 R and its direction as regards the position of the crank-handle n².

I claim:

1. A fuse setting device having an adjusting member adapted to change the adjustment of the fuse setting device corresponding to the desired distance of the bursting point; an operating member for setting the fuse and means connecting said adjusting member with said operating member, whereby the adjusting member is actuated to automatically change the adjustment of the fuse setting device when said operating member is being moved for setting the fuse.
2. A fuse setting device having an adjust-

ing member adapted to change the adjustment of the fuse setting device corresponding to the desired distance of the bursting point; an operating member for setting the 5 fuse and means connecting said adjusting member with said operating member, said connecting means composing a change speed gear whereby the adjusting member is actuated to automatically change the adjustment 10 of the fuse setting device when said operating member is being moved for setting the fuse.

3. A fuse setting device having an adjusting member adapted to change the adjustment of the fuse setting device corresponding to the desired distance of the bursting point; an operating member for setting the fuse and a change speed gear connecting said 15 adjusting member with said operating member, said change speed gear having a reversing gear, whereby the adjusting member is actuated to automatically change the adjustment of the fuse device when said operating member is being moved for setting the 20 fuse.

4. A fuse setting device having a revolute adjusting member adapted to change the adjustment of the fuse setting device corresponding to the desired distance of the bursting 25 point; an operating member for setting the fuse; a plurality of followers coaxially mounted relatively to said adjusting member

and positively connected with said operating member to turn with different angular speeds when said operating member is being moved; and a coupling adapted to rigidly connect said adjusting member to either one of said followers.

5. A fuse setting device having a revolute 40 adjusting member adapted to change the adjustment of the fuse setting device corresponding to the desired distance of the bursting point; an operating member for setting the fuse; a plurality of annular followers of 45 different diameters coaxially mounted relatively to said adjusting member and positively connected with said operating member to turn with different angular speeds when said operating member is being moved, said followers being provided with a plurality of radial slots; a latch mounted on 50 said adjusting member to slide radially thereon and a spring-actuated stud in the latch adapted to engage any one of said slots; and rings interposed between the adjacent annular followers whereby said latch 55 will be retained radially in engagement with any one of said annular followers.

The foregoing specification signed at Bar-
men, Germany, this first day of June, 1912. 60
WILHELM SCHWARTZ. [L. S.]

In presence of—
ALBERT NUFER,
HELEN NUFER.
